FIG. 1

FIG. 2

FIG. 3

FIG. 4

FIG. 1 is a perspective view of a vehicle door mirror mounting bracket embodying our new design;

FIG. 2 is a side elevational view thereof, the opposite side being similar in appearance;

FIG. 3 is a top plan view thereof; and

FIG. 4 is a front elevational view thereof.

The broken lines seen in FIGS. 1 and 2 represent variable environmental elements which form no part of the present design.

We claim:

The ornamental design for a vehicle door mirror mounting bracket, substantially as shown and described.
